(57) **CLAIM**

An ornamental design for a dispenser for flowable personal care products, as shown and described.

DESCRIPTION

FIG. 1 is a front, top and left side perspective view of a dispenser for flowable personal care products showing our new design;

FIG. 2 is a front elevational view thereof;

FIG. 3 is a rear elevational view thereof;

FIG. 4 is left side elevational view thereof, the right side elevational view being a mirror image of the left side elevational view;

FIG. 5 is a top plan view thereof;

FIG. 6 is a bottom plan view thereof;

FIG. 7 is a front, top and left side perspective view of an upper housing of the dispenser for flowable personal care products of FIG. 1, of an upper housing with base removed for ease of illustration;

FIG. 8 is a front elevational view thereof;

FIG. 9 is a rear elevational view thereof;

FIG. 10 is left side elevational view thereof, the right side elevational view being a mirror image of the left side elevational view;

FIG. 11 is a top plan view thereof;

FIG. 12 is a bottom plan view thereof;

FIG. 13 is a front, top and left side perspective view of a base of the dispenser for flowable personal care products of FIG. 1, of a base with upper housing removed for ease of illustration;

FIG. 14 is a front elevational view thereof, wherein the rear, left side, and right side elevational views are the same as the front elevational view;

(Continued)

FIG. 15 is a top plan view thereof; and,
 FIG. 16 is a bottom plan view thereof.
 The broken lines shown in the drawings depict features of
 the dispenser for flowable personal care products that form
 no part of the claimed design.
